UNITED STATES PATENT OFFICE

FRED W. SCHANTZ, OF LOUISVILLE, KENTUCKY

ASH RECEIVER FOR FURNACES

Application filed May 16, 1929. Serial No. 363,526.

The present invention appertains to new and useful improvements in ash receivers for furnaces, particularly to a novel receiver for ashes.

5 The principal object of the invention is to provide a receiver into which ashes dropping from the furnace grate will be guided and prevented from falling exteriorly of the receptacle part of the invention.

10 Another important object of the invention is to provide a guide for directing ashes falling down from the furnace grate into an underlying ash pan.

15 Another object of importance is to provide an ash receiver for furnaces which in use will eliminate the necessity of removing ashes not caught by the pan, which is now required in furnaces where ash pans are used.

20 Numerous other objects and advantages will become apparent as the invention is better understood from the following specification and claim.

In the drawings:—

25 Figure 1 represents a side elevation of the improved receiver.

Fig. 2 represents an end elevation of the invention.

30 Fig. 3 represents an end elevation looking at the opposite end of the structure from that shown in Fig. 2.

Referring to the drawings, wherein like numerals designate like parts, the invention includes an ash tray or receptacle generally referred to by numeral 5, and a guide for disposition above the receptacle and generally referred to in the drawings by numeral 6. The guide 6 includes a horizontally disposed U-shaped frame 7, supported by vertically disposed leg members 8.

40 The frame 7 is secured at 9, to the intermediate portion of the legs 8 and the upper portions of the legs 8 are declined inwardly as at 10, for attachment to the outer sides of the inclined side and end walls 11—11 and 12 respectively.

The end wall 12 is curved at its ends 13 to engage against the curved adjacent end 14 of the end walls 11—11. The lower edges 50 of the side walls are in right angular rela-

tion to each other so that a substantially rectangular opening is provided through which ashes may be guided into the receptacle 5.

The receptacle 5 has a bottom wall as well as side walls 15 and one end wall 16. The upper edge of the receptacle is preferably rolled as at 17 over a suitable reinforcing element. The single end wall is to be regarded as the rear wall of the receptacle while the front wall amounts to a narrow 60 forwardly inclined flange 17' merging with the forward declining ends of the side walls 15, which have their upper edges also rolled to receive reinforcing means.

A U-shaped member 18 serves as a bail 65 for the receptacle, the same having a finger engageable off-set 19 at its bight portion and its end bent inwardly for engagement within openings in the opposite sides 15 of the receptacle. Thus, by gripping the bail, the 70 receptacle may be easily removed from a disposition beneath the guide 6.

It is to be understood that while the guide means is shown in the drawings, supported by legs 8, the same may be cast in the construction of the furnace or otherwise secured to the furnace, without departing from the spirit of the invention or the scope of the appended claim.

From the foregoing description, it will be seen that the present invention embodies a simplified and inexpensive receiver for stoves and furnaces, which in use, will eliminate considerable labor now performed in removing ashes, not caught by the usual ash can.

Having thus described the invention, what I claim as new is:—

An ash receiver for furnaces comprising a pan, a U-shaped guide for directing falling ashes into said pan, a plurality of legs, a U-shaped frame for connecting said legs, the legs being inclined inwardly at their upper ends for supporting the guide in a slanting position.

In testimony whereof I affix my signature.

FRED W. SCHANTZ.
